TORPEDO WITH ROLLING HULL

Chester C. Wheeler, Altadena, Calif.

Application July 20, 1950, Serial No. 174,983

14 Claims. (Cl. 114—23)

(Granted under Title 35, U. S. Code (1952),
sec. 266)

1

This invention relates to fluid borne vehicles, and more particularly to an underwater vehicle such as a torpedo.

It is an object of this invention to provide improved stabilized guidance means for a torpedo.

It is another object of this invention to provide guidance means for a torpedo in which the casing or shell of the torpedo is allowed to freely revolve or roll about the carriage or chassis of the torpedo, so that only the latter need be stabilized, and the rolling forces on the casing need not be fought or compensated.

Other objects and many of the attendant advantages of this invention will be readily appreciated as the same becomes better understood by reference to the following description.

The torpedo of the instant invention comprises a carriage or chassis which is enclosed within an elongate casing or shell. The casing is rotatably mounted on the carriage so that it may freely roll thereabouts, and the carriage is stabilized by some suitable mechanism such as a gyroscope. The problem is then to transfer the control and guidance from the controlling means on the carriage to the outside of the casing, so that it may directly influence the attitude and course which the torpedo pursues.

This problem is met in the instant invention by the provision of two pairs of rudder controls disposed at right angles to each other and conversely of the torpedo which are so interlinked within the casing that the rudders automatically change position as the casing rolls about the carriage to continuously deflect the torpedo in the same direction, irrespective of rolling of the casing.

Two examples of means for practicing the instant invention have been illustrated in the following drawings, wherein:

Fig. 1 is a perspective schematic view illustrative of the principles of the instant invention;

Fig. 2 is a fragmentary, longitudinal cross-section of the invention illustrated schematically in Fig. 1; and

Fig. 3 illustrates a separate species of the instant invention.

Referring to Fig. 1, 11 designates a first body, in this case a torpedo carriage or chassis, stabilized in space by a suitable means such as a gyroscope (not shown). A second body is rotatably mounted to the carriage 11. This second body comprises a casing or shell 12 mounted around the carriage 11 by means of a series of roller bearings 13, so that the casing 12 is free to rotate or roll about the carriage 11 without affect-

ing the carriage in the least except for the slight frictional drag introduced through the roller bearings 13.

Pivoted in the casing 12 on an axis transverse to the torpedo axis is a first pair of aligned rudder shafts 14, which pass laterally through the casing 12, one on each side thereof. Rudders 16 are secured to the shafts 14. Spanning and connected to the facing ends of the shafts 14 is a generally semi-circular yoke 17, having a longitudinal slot 18 therein. A second pair of aligned shafts 19 is journaled in the casing 12 on an axis transverse to the axis of the shafts 14, and transverse to the longitudinal axis of the torpedo. The three axes cross at a common point in the center of the torpedo. Except for the 90° angular displacement, the shafts 19 are identical to the shafts 14, and have rudders 21 secured thereto externally of the casing 12 with a slotted yoke 22 secured to and spanning the facing ends of the shafts 19.

Along the longitudinal center line and axis of the carriage 11 (and of the entire torpedo) extends a stud 23 terminating in a universal joint 24 located at the crossing point of the three axes—shafts 14, shafts 19, and the torpedo axis. Universally mounted at the point 24 is a control rod 26, which extends through each of the slots 18 and 27 in the semi-circular yokes 17 and 22, respectively. A first pair of short control arms 28 extend from the control rod 26 near the base thereof, to the ends of which are universally mounted a pair of reciprocating rods 29, the position of which is controlled by any suitable control mechanism mounted on the carriage 11. A transverse pair of control arms 31 is similarly controlled by reciprocating rod 32, likewise controlled by any suitable mechanism mounted on the carriage 11. It will be readily evident that by suitable positioning of the reciprocating rods 29 and 32, the control rod 26 may be caused to assume any desired attitude in space with respect to the carriage 11. Remembering that the carriage 11 may be stabilized by gyroscopic means or otherwise, it will be seen that the orientation of the control rod 26 may be caused to remain fixed in spite of buffeting and rolling of the torpedo, and particularly of the torpedo casing 12.

The operation of the apparatus described thus far will now be explained. Assume that the torpedo is in the attitude shown in Fig. 1, so that the rudders 16 are in position to determine the course of the torpedo. Let it be assumed further that the control rod 26 is pointed downward at a small angle so that the rudders 21 are directed

straight ahead, while the rudders 16 are deflected so as to cause the torpedo to assume a downward course. Let it be assumed that the casing or shell 12 rolls 90° clockwise in Fig. 1, i. e. clockwise when viewed from the stern of the torpedo, while the carriage 11 remains stabilized. The effect on the shafts 19 will be that the slot 27 of the yoke 22 slides with respect to the control rod 26 and also rotates 90° with respect thereto until the yoke 22 occupies exactly the position that was previously occupied by the yoke 17. In a similar manner, the yoke 17 rotates 90° from its previous position and rotates and slides with respect to the control rod 26 until it occupies the position previously occupied by the yoke 22. It is readily obvious that the guidance of the torpedo will be the same as it was before the 90° rolling of the casing 12.

Furthermore, during the intermediate points of the rolling, the rudders 16 and 21 gradually assume their respective new positions, so that at all times the net effect of the four rudders 16 and 21 is always to direct the torpedo downward while still maintaining a straight ahead course. Thus, irrespective of the rolling of the casing 12 around the carriage 11, the rudders 16 and 21 are always controlled so that the effective guiding influence on the torpedo is directly in line with the orientation of the control rod 26. If the rod 26 is pointed not only down but also to one side, then both sets of rudders 16 and 21 will be offset from their straight ahead positions, and this net guiding direction will be maintained in effect through all positions of rolling of the casing 12.

It is therefore seen that there has been provided a means for translating a guiding effect from the stabilized carriage 11 to the exterior of the casing 12 while still permitting the casing 12 to roll freely about the carriage 11.

Certain structural details omitted in the schematic drawing of Fig. 1 for simplicity of explanation, are shown in the fragmentary longitudinal sectional view Fig. 2. As a matter of practical construction, it has been found desirable to effectuate the coupling between the control rod 26 and the slots 18 and 27 of the respective yokes 17 and 22, by means of intermediate bushings including roller bearings rotating about the control rod 26. For example, a bushing 41 is shaped to slide back and forth in the slot 27, the interior bore of the bushing being fitted with a roller bearing 42 which rolls around the surface of the control rod 26. A similar bushing 43 slides in slot 18 of the yoke 17, and has a corresponding roller bearing connection 44 with the control rod 26.

Another manner in which the instant invention may be practiced is illustrated in Fig. 3, wherein the control rod 26, universal joint 24, and reciprocating rods 32 and 29 are substantially the same as illustrated in Fig. 1. In this case, however, the control rod 26 may be considered as being constructed of two parts, the rod proper being pivotally mounted in a base or socket 46, the latter being the actual member which is universally mounted at 24. The rod 26 is then free to rotate in the socket 46 about its own axis. The necessity for this rotation will be brought out hereinafter.

Likewise, the paths of aligned shafts 14 and 19 are journalled in the casing 12, in substantially the same manner as shown in Fig. 1.

The significant difference is in the nature of the yokes 17 and 22 of Fig. 1. In the Fig. 3 species, these yokes assume the form of a pair of transverse arms 51 and 52, disposed at right an-

gles to each other in the form of a cross. Each of the arms is slotted longitudinally at the center as shown at 53 and 54, respectively, the rod 26 passing thru the slots. Pivot pins 56 and 57 maintain rod 26 at the midpoints of arms 51 and 52 respectively. Links 58 are pivoted respectively to the end of the transverse arm 51, the other end of each link being in turn pivotally secured to the respective, facing inward ends of the rudder control shafts 14. In an identical way, links 59 are pivoted to the respective ends of transverse arm 52, the other ends of the links being pivoted to the facing ends of the aligned rudder shafts 19.

The operation of the mechanism illustrated in Fig. 3 is as follows.

Let it be assumed that the reciprocating control rods 29 and 32 are operated so as to cause the control rod 26 to deflect angularly in a longitudinal plane passing through the transverse arm 52. This movement deflects the transverse arm 51 in an arc, and causes the rudder shafts 14 to rotate to their new positions. Movement of this nature is permitted by the transverse arm 52 through the angular deflection of the links 59, this movement occurring without disturbing the shafts 19 in the least. In a similar way the shafts 19 may be rotated to a new position by deflection of the control rod 26 in a longitudinal plane passing through the transverse rod 51, and finally a combination of the two control movements to any extent desired may be effected by deflecting the rod 26 in any direction.

Let it now be assumed that the control rod 26 is deflected downward in a longitudinal plane passing through the transverse arm 52 as shown in Fig. 3. Let it be assumed further that the shell 12 rolls 90° about its axis. Considering the movement of the arm 52, it will be seen that the links 59 which were originally deflected downward, will, as the arm 52 is turned to the position previously occupied by the arm 51 in Fig. 3, gradually be straightened up into a position paralleling the axis of the torpedo. At the same time the rudder control shafts 19 are being gradually rotated until the rudders 21 occupy the attitude formerly occupied by the rudders 16 on the shafts 14. In a similar manner, the transverse arm 51, which was initially deflected angularly so that its rudders 16 were deflected, will, as it is rotated 90°, assume the position formerly occupied by the arm 52, so that the rudder surfaces 16 are steadily brought into undeflected position, i. e. into a longitudinal plane passing through the axis of the torpedo.

In intermediate positions—between the full 90° arc movement assumed above—both rudder surfaces 16 and 21 will be partially deflected, the net aggregate effect of both deflections being always constant, so that the rolling of the casing 12 about its axis does not affect the guidance of the missile effected by the rudder surfaces 16 and 21.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. Control apparatus comprising a carriage, a casing rotatably mounted on said carriage for rolling about a first axis, a first pair of aligned

shafts journaled in said casing and disposed on an axis passing perpendicularly through said first axis, a second pair of aligned shafts journaled in said casing and disposed on an axis passing thru the juncture of said first two mentioned axes and perpendicular to each of said axes, rudder members on said shafts exteriorly of said casing, a first transverse arm extending between the facing ends of said first pair of shafts, a first pair of links connected between the respective ends of said first arm and the adjacent shaft ends, a second transverse arm extending between the facing ends of said second pair of shafts, a second pair of links connected between the respective ends of said second arm and the adjacent shaft ends, a control rod universally mounted on said carriage at the common juncture of said axes and extending thru the respective midpoints of said transverse arms, and pins pivotally securing said midpoints to said rod, whereby the effective attitude of said members with respect to said carriage is rendered independent of the rolling of said casing about said carriage.

2. Control apparatus comprising a carriage, a casing rotatably mounted on said carriage for rolling about a first axis, a first pair of aligned shafts journaled in said casing and disposed on an axis passing perpendicularly through said first axis, a second pair of aligned shafts journaled in said casing and disposed on an axis passing thru the juncture of said first two mentioned axes and perpendicular to each of said axes, a first transverse arm extending between the facing ends of said first pair of shafts, a first pair of links connected between the respective ends of said first arm and the adjacent shaft ends, a second transverse arm extending between the facing ends of said second pair of shafts, a second pair of links connected between the respective ends of said second arm and the adjacent shaft ends, a control rod universally mounted on said carriage at the common juncture of said axes and extending thru the respective midpoints of said transverse arms, and pins pivotally securing said midpoints to said rod, whereby the effective attitude of said rudders with respect to said carriage is rendered independent of the rolling of said casing about said carriage.

3. Control apparatus comprising a carriage, a casing rotatably mounted on said carriage for rolling about a first axis, a first pair of aligned shafts journaled in said casing and disposed on a second axis passing perpendicularly through said first axis, a second pair of aligned shafts journaled in said casing and disposed on a third axis passing thru the juncture of said first two mentioned axes and perpendicular to each of said axes, a first transverse arm extending between the facing ends of said first pair of shafts, a first pair of links connected between the respective ends of said first arm and the adjacent shaft ends, a second transverse arm extending between the facing ends of said second pair of shafts, a second pair of links connected between the respective ends of said second arm and the adjacent shaft ends, and a control rod movably mounted on said carriage and extending thru the respective midpoints of said transverse arms, whereby the effective attitude of said shafts with respect to said carriage is rendered independent of the rolling of said casing about said carriage.

4. Control apparatus comprising a carriage, a casing rotatably mounted on said carriage for

rolling about a first axis, a first pair of aligned shafts journaled in said casing and disposed on an axis passing perpendicularly through said first axis, a second pair of aligned shafts journaled in said casing and disposed on an axis passing thru the juncture of said first two mentioned axes and perpendicular to each of said axes, rudder members on said shafts exteriorly of said casing, a first slotted, generally semi-circular yoke secured to and spanning said first pair of shafts, a second slotted, generally semi-circular yoke secured to and spanning said second pair of shafts, and a control rod universally mounted on said carriage at the common juncture of said axes and extending thru the slots in said yokes to control the positioning thereof, whereby the effective attitude of said rudder members with respect to said carriage is rendered independent of the rolling of said casing about said carriage.

5. Control apparatus comprising a carriage, a casing rotatably mounted on said carriage for rolling about a first axis, a first pair of aligned shafts journaled in said casing and disposed on an axis passing perpendicularly through said first axis, a second pair of aligned shafts journaled in said casing and disposed on an axis passing thru the juncture of said first two mentioned axes and perpendicular to each of said axes, a first slotted, generally semi-circular yoke secured to and spanning said first pair of shafts, a second slotted, generally semi-circular yoke secured to and spanning said second pair of shafts, and a control rod universally mounted on said carriage at the common juncture of said axes and extending thru the slots in said yokes to control the positioning thereof, whereby the effective attitude of said shafts with respect to said carriage is rendered independent of the rolling of said casing about said carriage.

6. Control apparatus comprising a carriage, a casing rotatably mounted on said carriage for rolling about a first axis, a first pair of aligned shafts journaled in said casing and disposed on a second axis passing perpendicularly thru said first axis, a second pair of aligned shafts journaled in said casing and disposed on a third axis passing thru the juncture of said first two mentioned axes and perpendicular to each of said axes, a first slotted, generally semi-circular yoke secured to and spanning said first pair of shafts, a second slotted, generally semi-circular yoke secured to and spanning said second pair of shafts, and a control rod movably mounted on said carriage and extending thru the slots in said yokes to control the positioning thereof, whereby the effective attitude of said shafts with respect to said carriage is rendered independent of the rolling of said casing about said carriage.

7. A torpedo comprising a stabilized carriage, a pair of control means mounted on said carriage, an elongate torpedo shell surrounding said carriage and mounted thereon for rolling about the axis of said shell, a first pair of aligned shafts mounted pivotally, transversely, and diametrically in said shell, a second pair of aligned shafts similarly mounted in said shell at right angles to said first pair, rudders on said shafts exteriorly of said shell, a stud universally mounted on said carriage at the intersection of the axes of said first and second pairs of shafts, first push rod means connected between said stud and one of said control means to pivot said stud about its universal mounting in one plane, second push rod means connected between said stud and the other of said control means to

pivot said stud in a plane normal to said one plane, a first linkage member connecting said first pair of shafts, and a second linkage member connecting said second pair of shafts, both of said linkage members being engaged by said stud, whereby the direction of the torpedo is controlled by said stud in two planes irrespective of the rolling of said shell about said carriage.

8. A torpedo comprising a stabilized carriage, control means mounted on said carriage, an elongate torpedo shell surrounding said carriage and mounted thereon for rolling about the axis of said shell, a first pair of aligned shafts mounted pivotally, transversely, and diametrically in said shell, a second pair of aligned shafts similarly mounted in said shell at right angles to said first pair, rudders on said shafts exteriorly of said shell, a stud universally mounted on said carriage at the intersection of the axes of said first and second pairs of shafts, push rod means connected between said stud and said control means to pivot said stud about its universal mounting, a first linkage member connecting said first pair of shafts, and a second linkage member connecting said second pair of shafts, both of said linkage members being engaged by said stud, whereby the direction of the torpedo is controlled by said stud in two planes irrespective of the rolling of said shell about said carriage.

9. A torpedo comprising a carriage, an elongate torpedo shell surrounding said carriage and mounted thereon for rolling about the axis of said shell, a first pair of aligned shafts mounted pivotally, transversely, and diametrically in said shell, a second pair of aligned shafts similarly mounted in said shell at right angles to said first pair, rudders on said shafts exteriorly of said shell, a stud universally mounted on said carriage at the intersection of the axes of said first and second pairs of shafts, a first linkage member connecting said first pair of shafts, and a second linkage member connecting said second pair of shafts, both of said linkage members being engaged by said stud, whereby the direction of the torpedo is controlled by said stud in two planes irrespective of the rolling of said shell about said carriage.

10. Control apparatus comprising a carriage, a casing rotatably mounted on said carriage for rolling about a first axis, a first pair of aligned shafts journaled in said casing and disposed on an axis passing perpendicularly through said first axis, a second pair of aligned shafts journaled in said casing and disposed on an axis passing thru the juncture of said first two mentioned axes and perpendicular to each of said axes, rudder members on said shafts exteriorly of said casing, a control rod universally mounted on said carriage at the common juncture of said axes, a first linkage member connecting said first pair of shafts, and a second linkage member connecting said second pair of shafts, both of said linkage members being engaged by said control rod, whereby the effective attitude of said rudder members with respect to said carriage is rendered independent of the rolling of said casing about said carriage.

11. Control apparatus comprising a carriage, a casing rotatably mounted on said carriage for

5

rolling about a first axis, a first pair of aligned shafts journaled in said casing and disposed on an axis passing thru the juncture of said first two mentioned axes and perpendicular to each of said axes, a control rod universally mounted on said carriage at the common juncture of said axes, a first linkage member connecting said first pair of shafts, and a second linkage member connecting said second pair of shafts, both of said linkage members being engaged by said control rod, whereby the effective attitude of said shafts with respect to said carriage is rendered independent of the rolling of said casing about said carriage.

10

12. Control apparatus comprising a carriage, a casing rotatably mounted on said carriage for rolling about a first axis, a first pair of aligned shafts journaled in said casing and disposed on an axis passing perpendicularly through said first axis, a second pair of aligned shafts journaled in said casing and disposed on an axis passing thru the juncture of said first two mentioned axes and perpendicular on each of said axes, a control rod movably mounted to said carriage at the common juncture of said axes, a first linkage member connecting said first pair of shafts, and a second linkage member connecting said second pair of shafts, both of said linkage members being engaged by said control rod, whereby the effective attitude of said shafts with respect to said carriage is rendered independent of the rolling of said casing about said carriage.

20

13. Control apparatus comprising a first body, a second body rotatably mounted on said first body about a first axis, a first yoke having a first pair of aligned shafts projecting therefrom and journaled in said second body, the axis of said first pair of shafts passing perpendicularly thru said first axis, a second yoke having a second pair of aligned shafts projecting therefrom journaled in said second body, the axis of said second pair of shafts passing thru the juncture of said first mentioned axes and perpendicular to each axis, a control rod engaging said yokes, and a universal joint at said juncture mounting said rod on said first body.

30

14. Control apparatus comprising a first body, a second body rotatably mounted on said first body about a first axis, a first yoke having a first pair of aligned shafts projecting therefrom and journaled in said second body, the axis of said first pair of shafts passing perpendicularly thru said first axis, a second yoke having a second pair of aligned shafts projecting therefrom journaled in said second body, the axis of said second pair of shafts passing thru the juncture of said first mentioned axis and perpendicular to each axis, and a control rod engaging said yokes.
